METHOD FOR CRACKING OIL WITH ACCUMULATION UNDER PRESSURE

Charles A. Hillman, East Orange, N. J., assignor
to Standard Oil Development Company

Application April 20, 1931, Serial No. 531,312

2 Claims. (Cl. 196—48)

This invention relates to improvements in oil cracking equipment and methods, particularly with regard to the accumulation of charging stock. In a preferred embodiment, the invention 5 includes improvements in tube and tank cracking equipment in which an accumulator is operated at a pressure greater than that of the fractionating equipment.

The main object of the invention is to make 10 possible a high coil inlet temperature when charging a low boiling feed stock without using high pressure fractionating towers or exchangers. A temperature is maintained in the accumulator, without excessive vaporization of the 15 fresh feed stock, far above that obtainable when the accumulator is held at the pressure of the fractionating equipment. A further object of the invention is to provide means for utilizing the heat of the condensed oil to vaporize the lighter 20 fractions of the feed oil from the charging stock, thereby building up the pressure of the accumulator.

The invention will be fully understood from 25 the following description, read in connection with the accompanying drawing, in which the figure is a diagrammatic side elevation of a cracking plant comprising my improvements.

Referring to the drawing, reference numeral 1 30 denotes a cracking coil in a furnace setting 2, and discharging through a pipe 3 into the lower part of an enlarged thermally insulated reaction chamber or soaking drum 4. The cracking equipment itself is not a part of the present invention, and any approved type may be adopted.

The cracked product passes from near the top 35 of the soaking drum 4 through a pipe 5 into a tar separator 6. A pressure release valve 7 is installed in the pipe 5. A drawoff line 8 is connected to the separator 6 and leads to a tar cooler 9. Vapors pass from the separator through a 40 pipe 10 to a fractionation means, such as a bubble tower 11, preferably entering just above the bottom plate 12 therein. The fractionated product passes from the tower through a pipe 13 to a condensing coil 14 and a receiving drum 15. This latter has a vent pipe 16 in which pressure control valve 17 is installed.

Condensate formed in the tower and adapted 45 for recycling, is withdrawn to the accumulator 18 through line 19 by pump 20. When no increase of pressure is desirable in the accumulator, valve 21 controls the flow of condensate through line 21a to the accumulator 18, by-passing pump 20. Oil to be cracked is supplied to 50 the accumulator through line 22 and pump 23.

This line includes a heat exchange coil 24 arranged in the upper part of the tower 11.

The vapors formed in the accumulator 18 are withdrawn to bubble tower 11 by means of line 25. A pressure control valve 26 between accumulator 18 and bubble tower 11 regulates the 5 pressure. The combined liquid contents of the accumulator are forced by pump 27 through a pipe 28 to the inlet end of the cracking coil 1.

The operation of the process will be clear from 10 the following example in which it is assumed that heavy naphtha is to be cracked. The heavy naphtha is pumped through pipe 22 into accumulator 18 until the level therein stands about 15 as shown in the drawing. Pumping of the oil from the accumulator through pipe 28 into the cracking coil 1, which is suitably fired, is then begun. During the cracking period the temperature of the oil at the outlet of the coil will be held at about 950° F. and in the drum at about 20 890° F., the pressure in the coil and drum being about 1000 pounds per square inch. The pressure of the accumulator 18 is gradually built up to 270 pounds per square inch by means of the vaporization of the feed stock and pumps 23 and 25 20, valve 21 being closed and pressure relief valve 26 being set at 270 pounds per square inch.

The valve 7 will be set to give a pressure of 27 about 1000 pounds on the soaker. A pressure of 100 pounds per square inch is maintained 30 throughout the rest of the system by means of valve 17 on the receiving drum 15. In some cases it is desirable to maintain a higher pressure in the fractionating equipment, for example 150 pounds per square inch, though this may vary 35 with the characteristics desired in the product.

The temperature of the tar, if any is present 40 in the separator 6, will be about 750° F. when working at 100 pounds pressure, and the vapors emerge from the separator at about the same 45 temperature. At this temperature and 100 pounds pressure, kerosene and heavy naphtha will pass over with the gasoline into the bubble tower. The kerosene and/or any heavier distillate fraction produced is separately collected 45 and returned to the accumulator.

The accumulator may be maintained at a pressure (e. g. 200 to 300 pounds per square inch) substantially greater than in the fractionating equipment, and a temperature of 500° F. to 600° F. 50 The pressure maintained is due to pumps 20, 23, the pressure of which is counterbalanced by the vapor pressure of the accumulator stock, and, as stated, may be 270 pounds per square inch in the particular case herein described. At this 55

temperature and pressure a fraction of the heavy naphtha is vaporized and will pass to the bubble tower by pipe line 25, in order to maintain the desired pressure in the accumulator. The valve 5 26 may be set to give the required pressure differential between the accumulator and the bubble tower.

The present invention makes efficient use of the heating and distilling effect of the hot cracked 10 product. High pressure exchangers are not required nor is the showering of oil through the bubble tower used to obtain preheat, as has heretofore been proposed. Further, the accumulator pressure is maintained by removing a percentage 15 of the lighter fractions of the feed stock boiling below the end point of the desired distillate, thus relieving the cracking coil and allowing it to work in a more satisfactory manner.

It will be understood that the invention is not 20 limited to operation upon the particular stock referred to, and that variations in temperature and pressure are permissible. Numerous changes and alternative arrangements may be made within the scope of the appended claims in which it is 25 my intention to claim all novelty inherent in the invention as broadly as the prior art permits.

I claim:

1. In the cracking of naphtha the improvement which comprises supplying the naphtha in the preheated condition to an accumulating zone, passing a portion of condensed cracked oil vapors thereinto from a fractionating zone, withdrawing oil from the accumulating zone and passing it through an elongated narrow heating zone where it is heated to cracking temperature, digesting the heated oil in an enlarged digesting zone while maintaining the heating and digesting 10 zones under high pressure, passing the hot fluid from the digesting zone into a tar separating zone, separately removing liquid tar and oil vapors from the separating zone and fractionating the removed oil vapors in said fractionating zone 15 to obtain a condensate and a vapor, condensing the vapor in a condensing zone, and maintaining a substantially higher pressure in the accumulating zone than in the fractionating zone. 5

2. The process according to claim 1 in which 20 a pressure of the magnitude of about 270 pounds per square inch is maintained on the accumulating zone and a pressure of about 100 pounds per square inch is maintained on the fractionating zone. 25

CHARLES A. HILLMAN.
